MINING MACHINE

James E. Tracy, Pomeroy, Ohio

Application June 28, 1939, Serial No. 281,691

10 Claims. (Cl. 262—9)

This invention relates to method and means for mining, and more particularly to machines for undercutting the breast of a vein or strata of earth, coal or other minable material, so that the material may be conveniently "shot down" into the miners' room or mining space.

Heretofore mining of this character has been conducted with the aid of relatively large, cumbersome, heavy and expensive machines which required large output of power, and entailed great expense in their handling, operating and maintenance. A popular mining machine now employed incorporates endless conveyors or chains which carry cutting tools or bits arranged to undercut the breast of coal or other minable material, and in undercutting a breast of coal these machines produce an excessive quantity of relatively small coal particles or "bug dust," and the cutting components are frequently damaged by their engagement with streaks of hard sulphur or other hard material present in the coal vein.

An object of this invention is to provide an improved method and mechanism for mining coal or other commercially valuable material.

Another object of this invention is to provide a relatively small and compact mining or coal cutting machine which may be operated to commercial advantage in both large and small mines, and under conditions where relatively shallow veins of coal are encountered and also under conditions in which very low "head room" is available.

A specific object of this invention is to provide a mining machine in which a single auger, drill or cutting arm is fed while being driven for drilling or cutting operation axially into the breast of the material being mined, and then moved laterally while under cutting operation to produce an undercut or kerf along the breast of the vein of minable material.

Another object of this invention is to provide a mining machine incorporating novel instrumentalities for undercutting or producing a kerf or recess in the breast or vein of minable material, and for drilling shot apertures or recess above the said undercutting so that the vein of minable material may be readily shot down into the clearing or miners' room.

A more specific object of this invention is to provide a mining machine in which a single auger, drill or cutting arm is fed into the breast or vein of minable material while the said auger is being driven to impart thereto both rotary and reciprocatory motion, and then moving the

machine laterally so that the driven auger produces an undercut kerf or horizontally-disposed recess in the breast of the minable material.

A further object of this invention is to provide a mining machine in which a tapered auger, drill or cutting tool is fed axially while being driven for both rotary and reciprocatory operation, so that a tapered frusto-conical recess is initially cut for a predetermined distance into the breast of the material being mined and then moving the tapered auger laterally so that an outwardly tapering kerf or recess is cut across the breast of the material being mined.

It is also an object of this invention to provide a mining machine of generally improved construction, whereby the device will be simple, durable and inexpensive in construction, as well as convenient, practical, serviceable and efficient in its use.

20 With the foregoing and other objects in view, which will appear as the description proceeds, the invention resides in the combination and arrangement of parts and in the details of construction hereinafter described and claimed, it being understood that various changes in form, proportion, and minor details of construction may be made within the scope of the claims without departing from the spirit or sacrificing any advantages of the invention.

25 For a complete disclosure of the invention, a detailed description of the improved mining method and mechanism will now be given in connection with the accompanying drawings forming a part of the specification, wherein:

30 Figure 1 is a side elevation of the improved mining machine depicting it in operative position in a coal mine, a portion of the mine being shown in vertical section.

Figure 2 is a longitudinal vertical section taken through the improved mining machine,

Figure 3 is a plan view, parts appearing in section,

Figure 4 is an end view of the mining machine,

Figure 5 is a vertical detail sectional view,

Figure 6 is a vertical sectional view taken on the line 6—6 of Figure 1, and

Figure 7 is a side elevation of a preferred form of cutting arm or auger to be used in connection with the improved mining machine.

Referring to the drawings, in which similar reference characters designate corresponding parts, there is depicted the improved mining machine which includes a base 10 of the supporting frame of the machine, the base having a

bearing pedestal 11 secured to the upper face of one terminal thereof by bolts or other suitable securing devices 12. Bearing pedestals 13 and 15 are secured to the upper face of the base 10 by bolts, screws or other suitable securing devices 16, and at the upper terminal of the bearing pedestal 13 a bearing aperture 17 is formed in axial alignment with a similar bearing aperture 18 formed in the upper terminal of the bearing pedestal 11. A shaft 20 is rotatably secured within the bearing apertures 17 and 18, and this shaft is secured to and rotatably supports an elongated pinion 21, which meshes with a pinion 22, carried and driven by a motor 23, which is supported on a frame member or plate 25, which, in turn, is supported by the bearing pedestals 13 and 15.

Bearing apertures 26 and 27 are formed in the bearing pedestals 13 and 15 for the sliding reception of bearing sleeves or members 28 and 30. The axial dimension of the bearing sleeve 28 is greater than the axial dimension of the bearing aperture 26, and a suitable bearing 31 is secured against axial motion within the sleeve 28. A similar bearing 32 is secured against relative axial motion within the sleeve 30, and the bearings 31 and 32 may be of any preferred construction, such as sleeve bearings, or they may be any commercially acceptable antifriction bearings of the ball or the roller type. A shaft 33 is rotatably mounted in the bearings 31 and 32, and a gear 35 is secured to one terminal of this drill shaft 33, the gear 35 being constantly in mesh with the elongated pinion 21. The shaft 33 is held, at one terminal, against axial movement relative to the bearing member 31 by the inner face of the gear 35 and any suitable collar or sleeve indicated at 36, and this shaft is held at its opposed terminal against axial movement relative to the bearing 32 by the inner face 37 of an enlarged flange or disc 38 and a suitable collar or sleeve 40. Thus it is seen that the shaft 33 is rotatably supported in the bearings 31 and 32, but it is held against axial movement relative thereto, and the bearings 31 and 32 are held against axial movement within the axially movable bearing sleeves 28 and 30. The sleeves 28 and 30, in turn, are mounted for axial movement within the bearing apertures 26 and 27 of the bearing pedestals 13 and 15.

The inner terminal of the bearing sleeve 30 is provided with a gear housing or casing 42 having a worm 43 positioned therein, the worm being secured to and rotatable with the shaft 33. The worm 43 meshes with a worm gear 45 rigidly secured to and carried by a shaft 46 which is rotatably mounted in bearing apertures 47 and 48 formed in the gear housing 42. One terminal of the shaft 46 has a crank disk 50 keyed or otherwise rigidly secured thereto, the crank being positioned externally of the gear housing 42. A link or pitman 51 is pivotally secured to the crank disk 50 by a bolt or wrist pin 53, and the opposed terminal of the link or pitman 51 is pivotally secured to a slidable plate or member 54 by a suitable bolt or pin 55. The plate 54 is slidably mounted in a longitudinally extending aperture 56 formed in the bearing pedestal 13. The terminal of the slidable plate or member 54 which is remote from its pivotal connection with the pitman 51 is provided with aligned apertures 57 which receive a pin or bolt 58 that extends through an ear 60 formed at the outer terminal of a latch or stop member 61, so that this latch or stop member 61 is pivotally

secured to the outer terminal of the slidable plate or member 54. A manipulating handle or knob 62 is secured to the upper face of the stop member or latch 61 to provide convenient means for manually moving the latch or stop member 61 about its pivot or fulcrum pin 58. When the latch 61 is in normal position resting upon the upper face of the slidable plate 54 its outer terminal 63 engages a face of the bearing pedestal 13 to thereby lock the slidable plate against longitudinal movement, which action will be hereinafter more fully disclosed.

A block or supporting member 65 is slidably received within an elongated slot 66 formed in the link or pitman 51, and ears 67 extend laterally across the link or pitman 51 from each terminal of the block 65, which ears are disposed in opposition and may be bolted or otherwise suitably secured to the block 65. A bolt 68 extends through suitable apertures formed in the outer terminal of the ears 67 so that the ears may be clamped to the opposed faces of the link or pitman 51 to thereby lock or secure the block in any desired position in the elongated slot 66, to provide an adjustment which will be more fully disclosed hereinafter. Opposed links 70 and 71 are pivotally secured to the block 65, as indicated at 72, and the terminals of the links 70 and 71 which are remote from their pivotal connection 30 with the block 65 are pivotally secured to arms 73 and 75, as indicated at 76 and 77. The arm 73 has a pawl 78 pivotally secured thereto, as indicated at 80, and the arm 75 has a similar pawl 81 pivotally secured thereto, as indicated at 82, and the pawls 80 and 81 are normally constrained towards and engage the teeth 83 of a ratchet 85 secured to a shaft 86 rotatably supported by the base 13 of the machine frame. A drum or spool 87 is secured to and rotates with the shaft 86, and it has a suitable length of cable or other flexible element 88 wound about the peripheral portion thereof. The cable 88 leads outwardly from the spool or drum 87 around a sheave or guide pulley 90 and it has its outer terminal, not shown, suitably secured to any fixed object within the mine, for reasons to be hereinafter disclosed. A spool or drum 91 is rotatably secured to the machine base 10, as indicated at 92, and this drum is preferably held against rotation in one direction by a ratchet 93 which is normally engaged by a pawl 94. A cable or other flexible element 95 is carried by the drum and leads therefrom to any suitable destination within the mine, as will be hereinafter more fully explained.

The enlarged flange or disc 38 carried by the drill shaft 33 is designed to actuate a mining drill or auger of any suitable construction, and in the present instance, as best depicted in Figure 60 7, there is provided a cutting arm, drill or auger 96, preferably formed by spirally disposing ribs or flanges 97 about a central or axial stiffening rod or shaft 98. At one terminal of the cutting arm or auger 96 the ribs 97 and stiffening shaft 98 lead to a head or flange 100 having an upwardly boss or lug 101 extending transversely or diametrically thereacross. The boss 101 is adapted to be received in a complementary recess 39 formed in the shaft head or flange 33, the recess 39 extending diametrically across the outer face of the flange 33. Securing apertures 102 extend around the peripheral portion of the securing flange 100 for the reception of bolts or other securing devices 103 which extend through the flanges 33 and 100 to thereby rigidly secure

the auger or drill flange 100 to the shaft flange or head 38, with the diametrically extending boss 101 of the flange 38 accurately engaging the diametrically extending recess 39 formed in the shaft head 38. By this arrangement the securing bolts 103 are relieved of all torsional stress because of the accurate engagement of the diametrically extending boss 101 with the diametrically extending recess 39.

The drill or auger 96 may be of any suitable length, and usually a length from 4 to 6 feet is commercially acceptable. The inner terminal of the auger is of greater diameter than its outer terminal, the inner terminal preferably being about 6", and the auger tapers outwardly from this point to its outer terminal which preferably has a diametrical dimension of about 2". At regularly spaced intervals along the helically disposed ribs 97 there are provided apertures 105 for the reception of suitable cutting bits or tools 106 which are secured within the apertures by screws or other suitable securing devices 107.

As will be hereinafter explained, the drill shaft 33 both rotates and reciprocates, and its reciprocatory movement is preferably about 6". The reciprocatory movement of the shaft 33, of course, imparts a reciprocatory motion to the drill or auger 96 of like amplitude, and the cutting tools or bits are preferably spaced apart a distance somewhat less than the amplitude of axial movement of the drill or auger, which feature will be more fully explained hereinafter. The outer terminal of the helically disposed ribs 97 preferably terminate in laterally flaring cutting members or teeth 108 to affect the initial cutting during the drilling operation.

The "shot" or explosive charge is usually positioned above the undercut recess in order that the coal may be shot down into the miners' room, therefore to provide convenient and expeditious means for drilling the shot hole or aperture, a power drill is operated from the drilling machine. This drill includes an upright frame or housing 110, which may be bolted or otherwise secured to the machine frame, as indicated at 111. A cross head or block 112 is mounted for vertical sliding movement in the drill housing or frame 110, and opposed bearing members or rings 113 are carried by the block 112 and extend inwardly towards each other. The outer cylindrical faces 115 of the bearing rings 113 rotatably support bearing flanges 116 of a sprocket 117, and the bearing rings 113 are also provided with inner spherical bearing surfaces 118, which support a spherical drill socket 120 for universal movement. Gear teeth 121 are formed around the peripheral portion of the drill socket 120 and mesh with gear teeth 122 formed within the sprocket 117. A drill or auger shaft 123 is mounted for sliding movement within the drill socket 120, and this shaft 123 is held against rotary motion relative to the socket 120 by a key or other suitable securing device 125. The inner terminal of the drill or auger shaft 123 is threaded, as indicated at 126, which threads engage similar threads 127 formed internally of a manipulating nut or wheel 128. An annular groove 130 is formed in the hub of the manipulating wheel 128 for the reception of an annular flange 131 extending inwardly from a split annulus or ring 132. A cross bar or rail 133 extends horizontally across the upper portion of the drill or auger frame 110, and this bar or rail is internally threaded as indicated at 135 to threadedly engage a threaded stem 136 which is secured to and extends upwardly from the cross

head or block 112. A threaded manipulating nut or wheel 137 threadedly engages the stem 136, and this hand wheel or nut 137 is held against axial movement by a split ring or annulus 138 which engages an annular groove 140 formed in the peripheral portion of the nut 137. The outer terminal of the drill shaft 123 is provided with any suitable drill or auger 124 having a diametrical dimension suitable for drilling the usual shot hole or opening, indicated at H in Figure 1.

In order to drive the drill shaft 123, a chain or other flexible driving element 142 is trained around the sprocket 117. From this point the chain leads downwardly around a spring stressed idler sprocket 143, and then around a drive sprocket 145. The drive sprocket 145 is carried by a stub shaft 146 mounted in suitable bearings in the machine frame, and a clutch 147 is slidably mounted on the shaft 146 but is keyed against rotation relative thereto. The clutch member 147 may be moved to and from engagement with a similar clutch member 148, driven by the motor 23, by a manipulating handle or lever 150.

In operation, the machine frame is moved in predetermined position in front of the breast of coal or material to be mined and the motor is put in operation to drive the operating components of the machine. This causes the shaft 133 to rotate, and its rotation, in turn, imparts rotary motion to the crank 50 through the interposed worm 43 and worm gear 45. Assuming the latch member or stop 61 is in lowered position, as indicated in Figure 2, the rotation of the crank 50 moves the entire shaft assembly back and forth, and the amplitude of this reciprocatory motion is determined by the amplitude of offset of the wrist pin 53. Since the driven shaft 103 both rotates and reciprocates, this rotary and reciprocatory motion is imparted to the drill or auger 96, thus causing the auger 96 to cut a tapered aperture into the breast of coal or material being mined, as best indicated in Figure 1. As the crank 50 rotates, rocking motion is imparted to the pitman or link 51, which, in turn, imparts oscillatory motion of the arms 73 and 75 which causes the pawls 78 and 81 to engage the teeth 83 of the ratchet 85 to thereby rotate the cable drum 87. As the cable drum 87 rotates, it draws in the cable 88 and thus feeds the machine in any desired direction, dependent on the location of the anchored outer terminal of the cable. While feeding the auger or drill axially into the coal breast the cable extends forwardly, as indicated at 88a in Figure 3, and its outer terminal is secured to any suitable stationary object in the mine so that the drill is fed axially into the coal breast. After the drill or auger 96 has drilled into the coal breast the desired distance, usually from 4 to 6 feet, then the cable 88 is led outwardly around the pulley or sheave 90, as indicated at 88b in Figure 3. The forward movement of the drill or auger 96 is thus discontinued but the drill continues to rotate and reciprocate, and, at the same time, the entire machine is fed transversely across the breast, to thus cut a tapered horizontally disposed slot or recess S the desired distance across the coal breast, as best seen in Figure 1. If it is desired to operate the cable drum 87 without reciprocating the drill or auger shaft 33, the latch or block 61 is swung rearwardly away from the bearing pedestal 13, so that the shaft 33 and its housing remain stationary, but the plate 54 reciprocates. The resultant motion imparted to the pitman 51 by the liberation

of the plate 54 continues to operate the drum 87 through the hereinbefore described instrumentalities. If it is desired to vary the amplitude of rocking movement imparted to the arms 73 and 75, this may be accomplished by releasing the screw or bolt 68 so that the block 65 may be slid longitudinally within the recess 66. By this arrangement the speed of operation of the cable drum 87 may be varied simply by adjustably sliding the block 65 in the slot 66 of the pitman or link 51. The horizontally-extending tapered slot S is disposed so that its outer terminal has a greater vertical dimension than its inner terminal, the vertical dimension of the outer terminal being preferably about 6" and the vertical dimension of its inner terminal being preferably about 2". After the tapered recess has been cut across the coal breast, the clutch lever 150 is manipulated to cause the clutch member 147 to engage the clutch member 148, thus imparting rotary motion to the sprocket 145. The sprocket 145, in turn, imparts rotary motion to the sprocket 117 through the interposed chain 142, thereby imparting rotary motion to the drill or auger shaft 123 and auger 124. The auger 124 is then fed axially forwardly to cause it to drill the shot hole or aperture H the required depth into the coal breast. The shot hole or aperture H is preferably positioned above the undercut tapered slot or recess S, and, since the drill or auger shaft 123 is mounted for universal movement, this shot hole or aperture may be formed at any desired angle, as indicated in dotted lines in Figure 1.

By rotating the hand wheel or nut 128, the shaft 123 may be fed axially inwardly or outwardly, and by tilting the shaft 123 it may be disposed at any desired angle within the range of its movement relative to the face of the breast of coal. Universal movement of the drill or auger shaft 123 is permitted because the spherical drill socket 120 is mounted for universal movement within the bearings 113. Furthermore, the drill or auger shaft 123 may be vertically adjusted by rotating or manipulating the hand wheel 137. The rotation of the hand wheel 137 causes the cross head 112 to move upwardly and downwardly to thus permit the shot aperture or hole H to be drilled any desired distance above the undercut slot or recess S.

After the undercut recess or slot S has been formed and the shot hole H drilled, then the machine is moved a safe distance away from the coal breast preparatory to firing the shot. When the shot is fired the resultant loose coal will impinge the inclined lower wall of the undercut slot or recess S, thereby causing the coal to fall outwardly into the miners' room for quick, convenient and easy access. Thus it is seen that by forming the undercut slot or recess S of tapered configuration, the coal loosened by the fired shot will fall outwardly into the miners' room rather than remaining in the coal breast.

In moving the machine towards the coal breast or laterally across the coal breast, by the action of the cable drum 87 and cable 88, the machine tends to move around or creep away from the drill owing to the drill resistance. This creeping or turning action of the machine, however, may be arrested by the proper manipulation of the cable 95 through its drum 91 and ratchet lock. The outer terminal of the cable 95 may be secured to any fixed object in the mine, not shown, to thus anchor this terminal of the machine against movement. The cable drum 91 may be either hand driven or power driven, but,

inasmuch as this driving mechanism does not form a specific feature of this invention it has not been disclosed herein.

In phases of the operation of the machine it is desirable to operate the cable drum 87 without imparting reciprocatory motion to the drill or auger shaft 33 and the auger 96. In this event the manipulating knob 62 of the latch 61 is grasped and moved rearwardly about its hinge or fulcrum pin 58 away from the bearing pedestal 13. In this position of the components the slideable plate 54 slides back and forth, and, consequently, the drill or auger shaft 33 remains axially stationary, but the rocking motion of the pitman 51 causes the cable drum 87 to rotate through the instrumentalities hereinbefore disclosed, thus permitting the cable 88 to be employed to move the machine to any desired location within the mine.

By simultaneously rotating and reciprocating the cutting arm or auger 96 the efficiency of the coal cutting or mining machine is greatly enhanced. As hereinbefore stated, the amplitude of reciprocatory motion of the auger 96 is about 6" and the cutting bits or tools 106 are spaced apart a distance preferably 5", or some dimension slightly less than 6", so that in each reciprocatory movement of the auger 96, each tool travels axially a distance to slightly overlap the cutting zone or area of the next adjacent tool. By this arrangement, a relatively small number of cutting bits may be employed, and, at the same time, a sharp clean cut is effected, thereby saving power and also increasing the speed of operation of the cutting tool or auger.

Having thus described my invention, what I claim as new and useful is:

1. In a mining machine, a frame, a shaft mounted for rotary and axial reciprocatory movement, means for imparting rotary movement to the said shaft, means for imparting reciprocatory motion to the said shaft, an auger secured to the said shaft so that the rotary and reciprocatory movement of the shaft is imparted to the said auger, a rotatable cable drum, a rotatable member rotatably driven by the shaft, means operably connecting the cable drum with the rotatable member whereby the rotation of the rotatable member imparts intermittent rotary movement to the drum, and a cable leading from the drum to a fixed member external of the machine.

2. In a mining machine, a frame, a shaft mounted for rotary and axial reciprocatory movement, drive means for imparting rotary movement to the said shaft, means for imparting reciprocatory motion to the said shaft, an auger secured to the said shaft so that the rotary and reciprocatory movement of the shaft is imparted to the said auger, a rotatable cable drum, power imparting means operably interposed between the cable drum and the shaft to thereby impart intermittent rotary movement to the drum by the movement of the shaft, a cable leading from the drum to a fixed member external of the machine whereby the movable cable moves the machine, and means for adjusting the said power imparting means to vary the amplitude of rotary movement imparted to the cable drum from the said shaft.

3. In a mining machine, a frame, a shaft mounted for rotary and axial reciprocatory movement, a gear carried by the shaft and axially movable therewith, an elongated fixed gear meshing with the axially movable gear, power

imparting means, a pinion driven by the power imparting means and meshing with the elongated fixed gear to thereby drive the elongated fixed gear and axially movable gear to impart rotary motion to the shaft, a crank rotatable with the shaft, a fixed member, means carried by the shaft for imparting rotary motion to the crank, a pitman operably interposed between the fixed member and the crank to thereby impart axial reciprocatory motion to the shaft when the crank rotates, and an auger secured to the shaft.

4. In a mining machine, a frame, a shaft mounted for rotary and axial reciprocatory movement, a gear carried by the shaft and axially movable therewith, an elongated fixed gear meshing with the axially movable gear, power imparting means, a pinion driven by the power imparting means and meshing with the elongated fixed gear to thereby drive the elongated fixed gear and axially movable gear to impart rotary motion to the shaft, a crank rotatable with the shaft, a slideable member, a latch arranged to lock the slideable member in fixed relation to the machine frame, means carried by the shaft for imparting rotary motion to the crank, and a pitman operably interposed between the slideable member and the crank to thereby impart axial reciprocatory motion to the shaft when the slideable member is locked in fixed relation to the machine frame or to impart reciprocatory motion to the slideable member when the latch is adjusted to permit the slideable member to move relative to the machine frame.

5. In a mining machine, a frame, a shaft mounted for rotary and axial reciprocatory movement, means for imparting rotary movement to the shaft, a rotatable member rotatably driven by and bodily movable with the shaft, a member fixed relative to the frame, means for operably connecting the rotatable member with the fixed member to impart reciprocatory movement to the shaft by the rotation of the rotatable member, and an auger secured to the said shaft so that the rotary and reciprocatory movement of the shaft is imparted to the said auger.

6. In a mining machine, a frame, a shaft mounted for rotary and axial reciprocatory movement, driving means for imparting rotary movement to the said shaft, a rotatable member rotatably driven by and bodily movable with the shaft, a member fixed relative to the frame, means for operably connecting the rotatable member with the fixed member to impart reciprocatory movement to the shaft by the rotation of the rotatable member, an auger secured to the said shaft so that the rotary and reciprocatory movement of the shaft is imparted to the auger, a support, a drill adjustably mounted on the support, and means for operably connecting the drill with the said driving means to drive the drill.

7. In a mining machine, a frame, a shaft mounted for rotary and axial reciprocatory movement, means for imparting rotary movement to the shaft, a rotatable member rotatably driven by and bodily movable with the shaft, a member fixed relative to the frame,

means for operably connecting the rotatable member with the fixed member to impart reciprocatory movement to the shaft by the rotation of the rotatable member, an auger secured to the shaft so that the rotary and axial reciprocatory movement of the shaft is imparted to the auger, a support, a drill mounted for adjusting movement on the support, and means for operably connecting the drill with the said driving means to impart rotary movement to the drill.

8. In a mining machine, a frame, an auger mounted for rotary and axial reciprocatory movement relative to the frame, means for imparting rotary movement to the auger, means for imparting reciprocatory motion to the auger, a fixed vertical support carried by the frame, a cross-head supported for vertical sliding movement by the fixed support, a bearing carried by the cross-head, a drill socket supported for adjusting movement in the bearing, a drill slidably supported by the drill socket and rotatable therewith, a sprocket rotatably supported by the bearing and operably connected with the drill socket to impart rotary movement thereto, means for operably connecting the sprocket with the auger driving means to drive the drill socket and drill, and means for vertically adjusting the cross head relative to the fixed support to thereby move the drill to or from the auger.

9. In a mining machine, a frame, an auger mounted for rotary and axial reciprocatory movement relative to the frame, means for imparting rotary movement to the auger, means for imparting reciprocatory motion to the auger, a fixed vertical support carried by the frame, a cross-head supported for vertical sliding movement by the fixed support, a bearing carried by the cross-head, a drill socket supported for adjusting movement in the bearing, a drill mounted for axial sliding movement within the drill socket, means for securing the drill against rotary movement relative to the drill socket, means supported by the drill socket for adjusting the drill axially relative to the drill socket, a sprocket rotatably supported by the bearing and operably connected with the drill socket to impart rotary movement thereto, means for operably connecting the sprocket with the auger driving means to drive the drill socket and drill, and means for vertically adjusting the crosshead relative to the fixed support to thereby move the drill to or from the auger.

10. In a mining machine, a frame, a fixed vertical support carried by the frame, a crosshead supported for vertical sliding movement by the fixed support, a bearing carried by the crosshead, a drill socket supported for limited pivotal movement in horizontal and vertical planes in the bearing, a drill slidably supported by the drill socket and rotatable therewith, a driven member operably supported by the frame, means for operably connecting the driven member with the said drill socket to thereby drive the drill, and means for adjusting the crosshead to thereby move the drill relative to the said frame.

JAMES E. TRACY.
